UNITED STATES PATENT OFFICE.

AARON H. WOLFF, OF NEW YORK, N. Y.

DESIGN FOR A GAS STOVE OR RADIATOR.

SPECIFICATION forming part of Design No. 29,843, dated December 20, 1898.

Application filed September 12, 1898; Serial No. 690,802. Term of patent 7 years.

To all whom it may concern:

Be it known that I, AARON H. WOLFF, a citizen of the United States, residing at New York, in the county and State of New York, have invented and produced a new and original Design for a Gas Stove or Radiator, of which the following is a specification, reference being had to the accompanying drawing, in which I have represented my design by a perspective view.

The leading features of my design for a gas stove or radiator consist of the raised scroll and leaflet ornaments and lattice-work of the truncated pyramidal base, the raised circular oval and leaflet ornaments of the vertical tubes, and the raised scroll leaflet and lattice ornaments of the two-part top and urn.

The design of the truncated pyramidal base A comprises the elevated curved edges *a* between the corner-legs *b*, the raised scroll ornaments *c* of the legs and *c'* along the edges, the pearl ornaments *d*, the leaflet ornaments *e e'*, the lattice-work *f*, and the plain band edge *h*.

The design of the circular vertical tubes B 25 comprises the raised circular center *o* and connected oval figures *r r'*, extending therefrom in opposite directions, and the leaflet ornaments *s* within the same.

The design of the top comprises the outward-flaring lower part C, with raised scroll and leaflet ornaments *i* and lattice-work *k*, the convex or arched upper part C', with rising center surmounted by an urn C'', with raised scroll and leaflet ornaments *l* and scroll 35 handles *n*.

What I claim is—

The design for a gas stove or radiator, substantially as herein shown and described.

Signed by me this 9th day of September, A. 40 D. 1898.

AARON H. WOLFF.
